UNITED STATES PATENT OFFICE.

CEVANUS VANTREES, OF BUTLER, MISSOURI.

VIGNETTER.

1,161,170.

Specification of Letters Patent.

Patented Nov. 23, 1915.

Application filed September 17, 1914. Serial No. 862,197.

To all whom it may concern:

Be it known that I, CEVANUS VANTREES, a citizen of the United States, residing at Butler, in the county of Bates and State of Missouri, have invented certain new and useful Improvements in Vignettters; and I do declare the following to be a full, clear, and exact description of the invention, such as will enable others skilled in the art to which

it appertains to make and use the same.

This invention relates to vignettters for use in connection with cameras, the principal object in view being to provide an improved device of this character by means of which the position of the vignette card may be shifted in accordance with the desires of the photographer without the necessity of his leaving his position at the rear of the camera.

To this end the invention aims to provide a structure the operating parts of which are all arranged so as to be manipulated at one end of the device, and include provision for altering the elevation of the card support and its distance from the camera, as well as for all angular adjustments about either a vertical or a horizontal axis.

With the above general object in view, the invention comprises certain novel features of construction and combinations of parts, the essential elements of which are set forth in the appended claims, and a preferred form of embodiment of which is hereinafter specifically described with reference to the drawing accompanying and forming a part of this specification.

In the drawing—Figure 1 is a side view of an apparatus embodying the present improvements; Fig. 2 is a longitudinal section through the same, on a larger scale, and partly broken away; Fig. 3 is a plan view of the apparatus; Fig. 4 is a front elevation of the same; Fig. 5 is a vertical section on the line V—V of Fig. 1, but on an enlarged scale; and Fig. 6 is an enlarged fragmentary detail of certain parts appearing in Fig. 5.

Referring to the drawing, the device is supported upon a bracket member of appropriate dimensions, the arms 2 of which are adapted to be clamped to a table 4 in the

desired relation to the camera (not shown) by means of thumb screws 5 operating in connection with movable clamps 6. The bracket is provided with a disk portion 8, the opposite faces of which are frictionally embraced by a pair of disks 10 and 12 held in proper engagement by a pin 14 and a thumb nut 16, between which nut and the adjacent disk 10 is interposed a coil spring 18. The disks 10 and 12 are designed to rotate together upon the pin 14 whenever the elevation of the vignette card is adjusted, said disks being locked together for such rotation by means of a lug 20 on the disk 10 extending in between a pair of radial lugs 22 on the disk 12 (see Figs. 1 and 6).

The disks 10 and 12 have recessed inner faces, leaving only their marginal portions in engagement with the disk portion 8, so that further resilient engagement between said parts is thus obtained in addition to the action of the spring 18.

The disk 12 is provided with a pair of supporting loops or rings 24 for accommodating a longitudinally sliding tubular member 26, which is of sufficient length to carry a vignette card supporting frame the proper distance in front of the camera and also project far enough in the opposite direction or to the rear to present the operating parts within convenient reach of the photographer. The tubular member is prevented from turning on its own axis by a key 28 along a portion of its length for which notches 30 are provided in the rings or loops 24. The key 28 is provided with a lug 29 at its front end for engagement with the front ring 24 and thereby limiting the movement of the tubular member 26 whenever it is turned into upright position for throwing the vignetter out of use. At the front end of the member 26 is a flange 32 from which projects laterally an arm 34, the end of which arm is provided with a pin 36 for pivotally supporting a bar 38 constituting the lower member of the vignette card supporting frame. Within loops 40 at opposite ends of the bar 38 is pivoted a wire framework 42 of suitable form and dimensions for embracing the side edges of the

vignette card 44, shown in Fig. 1 and in dotted lines in Fig. 4. The bar 38 is provided with a slot 46 toward one of its ends for receiving a pin 48 at the outer end of an arm 50 projecting laterally from a disk 52 at the front end of a rod 54 which is journaled within the tubular member 26. This rod extends entirely through the member 26 and projects beyond the opposite end thereof, where the rod is threaded (see Fig. 2) and fitted with a handle member 56, which also telescopes over the adjacent end of the member 26 and is made sufficiently heavy to aid in counterbalancing the parts on the opposite side of the pivot pin 14. Coiled about the end of the rod 54 is a spring 58 the opposite ends of which abut against the interior of the handle member 56 and the rear end of the tubular member 26, thereby acting to hold the disk 52 in proper position against the flange 32 at the front end of the member 26. After being properly adjusted, a set collar 60 and a set nut 62 are clamped in position at the front and rear, respectively, of the handle member 56. By means of the mechanism just described it is now obvious that the vignette card supporting frame may be readily rocked or tilted about the axis of the pin 36.

The parts whereby the inclination of the vignette card toward the front or the rear may be regulated will now be described. One of the loops or rings 24, and the flange 32, are provided with eyes 64 and 64' respectively for slidably accommodating a rod 66, an additional guiding and supporting loop 68 being also provided for said rod intermediate the eyes 64. At its rear end the rod 66 is threaded and secured by clamp nuts 70 to a lug 72 on a sleeve 74 mounted slidably on the tubular member 26, which sleeve has a rearwardly extending arm and finger engaging eye 76 whereby the rod may be manually operated. Within the sleeve 74 is mounted a curved leaf spring 78 to interpose slight friction to the movement of the sleeve, said spring having an upward extension whereby it is secured to the rod 66 by means of one of the clamp nuts 70. The front end of the rod 66 is bent laterally to form an arm 79 approximately parallel to the arm 34 and engaging an elongated loop 80 provided on the frame work 42, this form of attachment being required to accommodate the angular movements of the frame work produced by the operation of the arm 50. It will thus be seen that by sliding the sleeve 74 along the tubular member 26 the frame-work 42 is rocked upon its bearings within the loops 40.

From the foregoing description it will be apparent that a simple and conveniently operated means is provided for carrying out the objects of the invention. The pivotal movement of the apparatus as a whole about

the pin 14 provides for the necessary vertical movement of the card support for adjusting its elevation. Sliding the tubular member through its bearing loops 24 enables the distance of the card from the camera to be readily varied. And by manipulation of the rods 54 and 66 the card frame may be rocked or tilted about either of two horizontal axes for bringing the card into the proper position to accord with the wishes of the operator. All these operations for the adjustment of the card's position are controlled entirely from the rear end of the apparatus, so that it is unnecessary for the operator to leave his position at the rear of the camera.

While the foregoing represents what is now conceived to be the preferred form of the apparatus, the right is reserved to such formal changes and modifications as may fairly fall within the scope of the claims which follow.

Claims:

1. In a vignetter, the combination of a bracket, a longitudinal member provided with a frictional pivotal connection with said bracket for movement about a horizontal axis, said connection permitting longitudinal sliding of said member, a card support at one end of said member, and means operable from the other end of said member and having a pin and slot engagement with said card support for tilting the latter about an axis parallel with said longitudinal member.

2. In a vignetter, the combination of a bracket, a longitudinal member mounted on said bracket for movement both longitudinally and pivotally about a horizontal axis, an arm projecting laterally from one end of said member, a card supporting frame pivoted at the end of said arm, and means operable from the other end of said member and having sliding engagement with said supporting frame for tilting the latter about an axis parallel with said longitudinal member.

3. In a vignetter, the combination of a bracket, a longitudinal member mounted on said bracket for movement both longitudinally and pivotally about a horizontal axis, an arm projecting laterally from one end of said member, a card supporting frame pivoted at the end of said arm, and means connected with said supporting frame and having sliding and yielding frictional engagement longitudinally of said member for tilting said frame about an axis at right angles to said member.

4. In a vignetter, the combination of a bracket, a longitudinal member mounted on said bracket for movement both longitudinally and pivotally about a horizontal axis, an arm projecting laterally from one end of said member, a card supporting frame piv-

oted at the end of said arm, a member mounted axially of said longitudinal member and provided with yielding means tending frictionally to hold said members against relative rotative movement, and a connection 5 between said axially mounted member and said frame whereby rotation of the former will tilt the latter about an axis parallel to said longitudinal member.

10 5. A vignetter comprising, in combination, a bracket, a tubular member carried by said bracket, a card support carried by one end of said member, a rod journaled in said member, and a second rod mounted slidingly 15 on said member, said rods having connections to said card support for tilting the latter respectively about axes at right angles to each other, both of said rods being operable from the other end of said member and provided with means acting frictionally to 20 resist movement of said rods relatively to said member.

6. A vignetter comprising, in combination, a bracket, a tubular member mounted on 25 said bracket for movement both longitudinally and pivotally, a card support carried by one end of said member, a rod journaled in said member, and a second rod mounted slidingly on said member, said rods having 30 connections to said card support for tilting the latter about axes at right angles to each other, both of said rods being operable from the other end of said member and provided with yielding means acting to resist movement 35 of said rods relatively to said member.

7. A vignetter comprising, in combination, a bracket, a tubular member carried by said bracket, a card support carried by one end of said member, a rod journaled in said 40 member, a second rod mounted slidingly on said member, frictional means interposed between said rods and member for slightly resisting relative movements between them, and connections between said rods and said 45 card support for tilting the latter respectively about axes at right angles to each other, both of said rods being operable from the other end of said member.

8. In a vignetter, the combination of a 50 bracket having a disk portion, a pivot bolt carried by said disk portion, a pair of disks carried by said bolt on opposite sides of said disk portion and held yieldingly against the same, means connecting said disks for movement together, and card holding and 55 adjusting mechanism carried by one of said disks and mounted for movement thereon at right angles to said bolt.

9. In a vignetter, the combination of a 60 bracket having a disk portion, a pivot bolt carried by said disk portion, a pair of disks carried by said bolt on opposite sides of said disk portion and held yieldingly against the same, the inner faces of said disks being recessed and leaving their marginal portions

only in contact with said disk portion, means connecting said disks for movement together, and card holding and adjusting mechanism mounted on the outer face of one of said disks.

70

10. A vignetter comprising a bracket having a disk portion, a disk yieldingly clamped to said disk portion for pivotal movement thereon, a pair of loops carried by said disk, a longitudinal card supporting and adjusting member slidably mounted in said loops and provided with a longitudinal key, said loops being provided with notches for receiving said key, and a stop lug at one end of said key and adapted to engage one of 80 said loops for limiting the movement of said longitudinal member.

75

11. A vignetter comprising a bracket, a tubular member mounted on said bracket for movement both longitudinally and pivotally 85 about a horizontal axis, a card support carried by one end of said member, a rod journaled in said member and provided at one end with a connection to said card support for tilting the latter, the other end of said 90 rod having a resilient friction element abutting the adjacent end of said tubular member, and a handle member inclosing said friction element and the adjacent end of said tubular member and held in position 95 thereon to bind said friction element against the end of said tubular member.

85

12. A vignetter comprising a bracket, a tubular member mounted on said bracket for movement both longitudinally and pivotally 100 about a horizontal axis, a card support carried by one end of said member, a rod journaled in said member and provided at one end with a flange portion abutting the adjacent end of said member and with a connection to said card support for tilting the latter, the other end of said rod being provided with means for resiliently retracting said 105 rod and thereby holding said flange portion in yielding engagement with said adjacent 110 end of said tubular member.

105

13. A vignetter comprising a bracket, a longitudinal member carried by said bracket, a card support carried by one end of said member, a rod slidably mounted on said member and provided with a connection at one end to said card support for tilting the latter, a sleeve connected to the other end of said rod and embracing said member, said sleeve being provided with a handle for reciprocating the same, and a curved leaf spring carried by said rod adjacent the sleeve and extending in between the latter and said longitudinal member.

115

14. A vignetter comprising a bracket, a longitudinal member carried by said bracket, a card supporting frame carried by one end of said member and provided with an oblong loop extending horizontally at right angles 120 to said member, and a rod operable from the 130

other end of said member and carried slidably thereby, said rod having an arm having a slidable connection with said loop.

15. A vignetter comprising, in combination, a bracket, a longitudinal member mounted on said bracket for movement both longitudinally and pivotally about a horizontal axis, a card-support pivotally carried at one end of said member, and combined means 10 having yielding frictional engagement with said member and operable from the other end

thereof for tilting said card-support about either a horizontal axis at right angles to said member or an axis parallel to said member.

In testimony whereof I affix my signature in the presence of two witnesses.
